SADDLE

Roland W. Faulhaber, Monroeville, Ohio, assignor to The Faulhaber Company, Monroeville, Ohio, a corporation of Ohio

Application February 4, 1939, Serial No. 254,664

8 Claims. (Cl. 155—5.22)

This invention relates to saddles for bicycles, velocipedes and the like.

The principal feature of this invention is the provision of an ornamental and protective housing carried by the reach or spring supporting member of the saddle and covering the lower ends of the springs and the connections of the springs to the reach so as to conceal the relatively unsightly lower ends and connections of the springs and make the entire saddle more pleasing in appearance, and at the same time to prevent clothing or other articles or the hands of the user from being caught, torn or scratched by the lower ends of the springs or the connections of the springs to the reach.

Other features of this invention are an improved and simplified connection of the upper ends of the springs to the saddle base without the use of bolts, rivets or the like; an improved and simplified connection of the lower ends of the springs to the reach member; an improved reach; and a combination spring construction and ornamental and protective housing carried by the reach in which the housing aids in retaining the spring in cooperative relation with the reach member.

Other features and advantages of this invention will become apparent from the following detailed description of a preferred embodiment.

In the accompanying drawing:

Figure 1 is a side elevation of a saddle embodying the present invention;

Figure 2 is a longitudinal section through the saddle shown in Figure 1 taken substantially on the line 2—2 of Figure 3;

Figure 3 is a bottom plan view of the saddle shown in Figure 1;

Figure 4 is a detailed view partly in section and partly in plan taken substantially on the line 4—4 of Figure 2;

Figure 5 is a detailed sectional view taken on the line 5—5 of Figure 4;

Figure 6 is a perspective view of one of the housing members before being attached to the reach.

Referring to the drawing, the novel spring assembly of this invention is illustrated in combination with a seat, consisting generally of a sheet metal base member 10 having a relatively narrow front end or nose portion, flaring into a widened portion and terminating in an outwardly flared skirt 11. Suitable cushioning material 12 is disposed upon the seating portion of the base member 10 and is covered by a covering sheet of leather or other suitable material 13. The cov-

ering material extends completely over the forward or nose portion and in the illustrated embodiment likewise extends downwardly over at least the central part of the outwardly flared skirt member 11. Throughout the forward portion of the saddle the edges of the covering material are turned under the depending edges of the base member 10. In the illustrated embodiment suitable metal ornamental and protective members 14 are mounted upon the side portions of the outwardly flared skirt portion 11 of the base member and are provided with relatively narrow arms 15 extending across the center of the outwardly flared portion 11. The members 14 may be made as separate pieces with their arms 15 abutting at the center of the saddle or may be made in one piece. The members 14 preferably encompass the widest portion of the seat and thereby serve as buffers to protect the seat. The edge of the covering sheet 13 is secured under the edges of the metal members 14.

The reach member illustrated consists of a longitudinally arranged piece 16 of relatively stiff sheet metal stock having its forward end bent into a hook 17 to cooperate with a plate 18 riveted or otherwise suitably secured to the base member 10 and a laterally arranged channel piece 19 formed at its opposite ends to receive the lower ends of the springs. The forward end of the reach may be connected to the seat in any other suitable manner and a nose coil may be used if desired. Two coiled compression springs 20 are provided, each spring being connected to one end of the cross member 19 of the reach and to the seat. In accordance with one feature of the invention the cross member 19 is formed with flanges 21 which are turned inwardly adjacent the ends of the cross member 19 over the lowermost convolutions of the springs 20, as illustrated in Figures 4 and 5, to securely fasten the springs to the reach. The intermediate portion of the flanges 21 are slotted to receive the rear end of the longitudinal member 16, as illustrated in Figures 2 and 3, and the overlapping parts of the member 16 and 19 are secured together by spot welding, pressed detents, or the like.

According to another feature of the invention the springs are formed right and left hand and the upper ends are extended into tangential arms 22 which slidably fit within a sleeve member 23 formed on or secured to the base 10. As illustrated the sleeve 23 is formed by a plate 24 riveted or welded to the base 10 and having a portion bent into generally cylindrical form to fit

the extended arms 22 of the springs. The arms 22 and the sleeve member 23 are preferably of such length that it is necessary to distort the upper ends of the springs to force them within the flared skirt 11 and enter the arms 22 in the sleeve 23. The springs then return to their undistorted form and are held against separation by the adjacent side walls of the skirt member 11.

As an additional means for retaining the upper ends of the springs 20 in position, bosses 25 of a diameter substantially equal to the inside diameter of the springs are located within the upper ends of the springs. As illustrated, these bosses 25 are formed from pressed out portions of the base 10, but they may also be formed as parts 15 of the plate 24.

The ornamental and protective housings for the lower ends of the springs are preferably mounted upon the reach member 16 so as to extend below the reach and conceal and cover the lower ends of the springs and the connection of the springs with the reach. As illustrated these housings are formed as integral drawn sheet metal cups 27 having a generally tear drop or stream lined shape. Each housing is formed on one side with a slot 28 of a size to closely fit the end of the cross member 19 of the reach 16 and on the opposite side is formed with a pair of notches 29 separated by a lug 30, the notches 29 and lug 30 having a combined length equal to the width of the cross member 19. The cross member 19 is formed with a slot 31 of a size to receive the lug 30, these slots being spaced from the free ends of the cross member 19 a distance slightly greater than the width of the housings 27.

After the springs are assembled upon the reach member 16 as described above, the housings 27 are placed over the lower ends of the springs, the ends of the cross member 19 of the reach entered in the slots 28, and the lugs 30 projected through the slots 31 and bent over as illustrated in Figures 4 and 5. At the same time the lugs 30 are bent over, the turned down portions of the flanges 21 may be pressed tightly against the lowermost convolutions of the springs 20. The housings preferably have a width substantially equal to the outside diameter of the springs as illustrated in Figures 4 and 5 so that when they are secured in position they prevent sliding of the springs within the turned down portions of the flanges 21.

The entire reach and spring assembly is then connected to the seat member by turning the reach so that the hooked end 17 can be entered in the slot in the member 18 and then swinging the reach upwardly until the springs approach their proper positions against the under side of the base 10. The upper ends of the springs are then distorted so that the arms 22 may be forced into the sleeve 23 and the upper coils snapped over the bosses 25, and when so assembled the spring and reach assembly is securely connected with the seat.

It will be understood, of course, that the ornamental and protective housings 27 may be made of any desired shape to blend pleasingly with the seat itself or with the bicycle or velocipede upon which the seat is to be mounted. Likewise these housings can be secured to any desired type of reach and may be used with any desired type of connections of the springs to the seat and to the reach member. When mounted in position over the lower ends of the springs and the connections of the springs with the reach the housings 27 not only enhance the appearance of the saddle, but also prevent the clothing of the rider or other

articles from being caught or torn by the lower end of the springs or the spring connections and likewise prevent the hands of the user from being caught or scratched at these points.

5 In the preferred embodiment as illustrated the metal members 14 secured to the sides of the seat are formed with a generally tear drop or stream lined shape and the housings 27 are formed with a corresponding shape. Likewise, it is preferred to make both the members 14 and the housings 27 of bright metal such as stainless steel or plated metal to provide a vivid contrast with the relatively dark colored covering member 13 which covers all of the remainder of the visible portion of the seat. In some embodiments, however, the members 14 and the housings 27 are painted to harmonize with the coloring of the covering material 13 and the color scheme of the cycle.

Preferably an ornamental member of some kind is secured to the flared skirt member 11 at the rear of the saddle. As illustrated a sheet metal piece 32 having the general shape of an airplane is provided with a plurality of lugs projecting through the covering member 13 and the metal of the flared skirt portion 11 and turned over on the inside of the saddle to secure the ornamental member in place.

10 The novel spring connections to the seat and to the reach may likewise be used with any other type of seat or reach member if desired, although in the preferred embodiment as illustrated all of these various features are combined to provide a light, serviceable saddle having a striking and distinctive appearance that can be manufactured very economically.

15 The saddle illustrated may be secured to a cycle by a clamp on the reach member 16, as disclosed in my copending application, Serial No. 254,665, filed February 4, 1939, or a post may be riveted directly to the reach member 16.

20 Although the preferred embodiment of the invention has been described in considerable detail, it will be understood that many variations and modifications may be made therein without departing from the scope of the invention as defined in the following claims.

25 I claim:

1. A saddle for cycles and the like comprising a seat member, a reach member, means connecting the forward end of the reach member to the seat member, a pair of springs connected to the rear portions of the reach member and seat member, and a pair of ornamental and protective housings secured to the reach member and extending below said springs and said reach member, and below the connections between said springs and said reach member, each of said housings being generally cup-shaped with its upper end open and receiving and preventing contact with the lower end of one of said springs, and with its lower end closed and free of the loads transmitted by said springs to said reach.

2. A saddle for cycles and the like comprising a seat, a sheet metal generally T-shaped reach, means connecting the stem portion of the reach to the forward end of the seat, a pair of coil springs secured to the cross member of the reach with their axes disposed substantially normal to the cross member and to the seat, said springs being oppositely wound and having their upper ends extending toward each other, and a transversely extending sleeve member on the underside of said seat receiving the ends of said springs.

3. A saddle for cycles and the like comprising a

seat, a sheet metal generally T-shaped reach, means connecting the stem portion of the reach to the forward end of the seat, a pair of coil springs secured to the cross member of the reach, said springs being oppositely wound and having their upper ends straight and extending toward each other, a transversely extending sleeve member on the underside of said seat receiving the straight ends of said springs, and bosses projecting from the seat and fitting inside the upper ends of said springs.

4. A saddle for cycles and the like including a reach member having laterally extending arms, a coil spring secured to each of said arms, and a pair of ornamental and protective housings secured to said reach, each of said housings being generally cup-shaped and being formed with a slot on its outer side through which the end of one of said arms extends.

5. A saddle for cycles and the like including a reach member having laterally extending flanged arms, a coil spring carried by each of said arms, each of said springs having its lower portion disposed between its respective arm and the inwardly bent flanges thereof, and a pair of ornamental and protective housings secured to said arms, each of said housings being formed with a slot on its outer side through which the end of its respective arm extends, and means securing the inner sides of said housings to said arm.

6. A saddle for cycles and the like including a seat, a reach having its forward end connected to said seat, said reach having laterally extending flanged arms supporting coil springs, each of said springs having its lower portion disposed between its respective arm and the inwardly bent flanges thereof, the upper ends of said springs

having extended straight portions, and sleeve portions on the underside of said seat receiving said extended straight portions and constituting the sole means connecting the upper ends of said springs to said seat.

7. A saddle for cycles and the like, a seat member, a reach consisting of a longitudinally extending flat member having its forward end connected to the forward end of said seat member, and a laterally extending flanged member having its flanges formed with slots receiving the rear end of said longitudinally extending member, means securing the overlapping portions of said laterally and longitudinally extending members together and springs connected to said laterally extending member and to said seat member.

8. A saddle for cycles and the like comprising a seat member, a reach member, means connecting the forward end of the reach member to the seat member, a pair of coil springs having their upper ends connected to the rear portion of the seat member, means connecting the lower ends of said springs to the rear portion of the reach member so as to transmit loads from said springs directly through said means to the reach member, and a pair of ornamental and protective housings secured to the reach member, each of said housings comprising a drawn metal cup having its upper end open and receiving the lower end of one of said springs and being closed below said reach, said housings concealing and preventing contact with the lower ends of said springs but being free of the loads transmitted by said springs to said reach.

ROLAND W. FAULHABER.
